UNITED STATES PATENT OFFICE.

GEORGE A. ROBINSON, OF WOLLASTON, MASSACHUSETTS, ASSIGNOR TO PNEUMATIC SCALE CORPORATION, LTD., OF NORFOLK DOWNS, MASSACHUSETTS, A CORPORATION OF MASSACHUSETTS.

CARTON-FEEDING DEVICE.

Application filed October 16, 1922, Serial No. 594,796. Renewed July 29, 1926.

My present invention relates to packaging and filling devices and particularly to the handling of cartons in such machines. The particular problem with which my present invention deals centers around the opening up and forming of flat folded cartons so as to prepare them for the reception of their contents.

The usual commercial carton which is prepared and shipped flat involves certain inherent difficulties in getting it from its flat or folded state into its erected or opened up position by mechanical means.

This difficulty is primarily due to the natural "set" given to the carton while in its flat state with the folds at diagonally opposite corners, creased hard as they naturally become when closely packed together and the opposite corners flattened out. This "set" in the folded carton naturally makes it tend to stay closed and to return to a closed or partly collapsed condition after it is opened up.

It is obviously of great importance that the carton when set up be as truly rectangular as possible. The problem of handling has been variously treated in the art and a variety of opening up mechanisms have been devised.

My present invention includes in part certain novel instrumentalities and combinations by which a maximum of accuracy and speed is obtained with a minimum of waste due to tearing and crumpling of the paper cartons.

This, with various improvements in the feeding of the cartons to the opening up point and their subsequent delivery for succeeding operations according to my present invention may best be understood by reference to a practical embodiment and I have therefore shown in the accompanying drawings and will describe in the following specification a machine which I have tested out and which is in accordance with my invention and well illustrative thereof.

Throughout the specification and drawings like reference characters are employed to indicate corresponding parts, and in the drawings:

Fig. 1 is a side elevation of the feed portion of a machine in accordance with my invention.

Fig. 2 is a similar view from the opposite side. 55

Fig. 3 is a view from the right of Fig. 1 with the conveyor removed.

Fig. 4 is a somewhat enlarged view of the resistance feed at the delivery end of the conveyor. 60

Fig. 5 is a detail of the ratchet system of said feed.

Fig. 5^a is a further detail of the same in opposite phase of the throw.

Fig. 6 is a plan view of the cross feed head 65 of the machine.

Fig. 7 is a fragmentary plan view of the same area but stripped to show underlying parts.

Fig. 8 is a detail plan of the carton opening receiver. 70

Fig. 8^a is the same with the carton partly opened.

Fig. 8^b is a similar view showing carton entering a pocket in the turret head. 75

Fig. 9 is a somewhat enlarged detail of the carton pocket and its movable jaw.

Fig. 10 is a side view of the opening blade area.

Fig. 11 is a fragmentary plan view of the cross slide in its transferring movement, and

Fig. 12 is a detail of the carton follower.

In the embodiment of my machine which I have shown in these drawings as illustrative of my invention, I mount on a base 85 1 a slide frame or head 10 on which and on the base 1 are mounted slides 20 and 30.

The base 1 is formed with an overhang 11 as will be seen in Fig. 3, which supports the head 2 transversely of a conveyor frame 40 along which the knock down or flat cartons are advanced to the transfer slide 20. The conveyor 41 is of the chain feed type running on sprockets 42 to advance the vertically disposed pack of cartons longitudinally of the frame 40 and between the rails 43 supported on uprights 44 at each side of the way. The rails 43 are disposed two on one side of the conveyor 41 and one on the opposite side, the odd rail being disposed about midway the height of the two opposite rails so as to give a three point support for the stack of cartons as they move past. 100

The sprocket 42 is advanced by a ratchet drive comprising a ratchet 50 mounted fast on a shaft 51 and turned by a pawl 52 car-

ried by an arm 53 loosely mounted on shaft 51. This pawl is reset by an eccentric 60 on a shaft 61 through a rod 62 which is connected to an arm 54 integral with the arm 53 and disposed at substantially right angles thereto. The rod 62 has a forked end which embraces the eccentric 60 and is engaged thereby whenever the rod 62 lowers it. The arm 54 is also connected with a spring 55 fastened at 56 to the base of the machine and tending to rock the pawl arm 53 and thus turn the sprockets 42 to advance the carrier 41. This spring 55 constitutes a predetermined motive power to the conveyor 10 drive.

The return motion of the ratchet 52 is effected by the eccentric 60 which resets the pawl on the main power shaft 61 whenever the transfer slide has reduced the number of 20 cartons sufficiently to allow the spring 55 to draw down the arm 54 so that the eccentric 60 finds bearing at its bottom. It thus resets the ratchet to advance the carrier under the action of the spring 55 whenever 25 the reduction of pressure adjacent the transverse slide permits the action of the spring 55.

The spring 55 therefore keeps the pressure within predetermined limits on the 30 blanks in advance of the follower 45. This follower 45 consists of a heavy block having pins 46 in its lower face which engage with each of the conveyor chains 41. As the cartons are placed on the conveyor the block 45 is placed behind them as a follower to hold the cartons erect and to insure their advance and their free presentation to the transfer slide 20.

Referring to Fig. 7 which is a plan view 40 of the transfer slide head with the brackets 11 removed, the slide 20 is gibbed into a way 21 the entire width of the frame. It is reciprocated along this way by a lever 70 having a forked end 71 which receives 45 between its jaws a block 72 which is loosely pivoted on a stud 73 carried by the slide 20.

The lever 70 is pivoted at 74 to the bracket on the base 1. It carries at its lower end a roller 75 which runs in a cam slot 76 on a cam 77 which is fast on the power shaft 61. Mounted on a stud 73 is a bracket 80 carrying an adjustable stud 81 which is disposed to strike a jogger lever 82 pivoted at 83 and normally held up towards the bracket by a spring 84. This spring 84 is fastened at 85 to a bracket and at 86 to a hook which projects out from the end of the lever 82 opposite to that portion struck by the stop 81.

60 This jogger lever aligns the cartons on the conveyor 41 just after they leave the sprocket and are pushed forward to the transfer slide.

At the end of the slide way 21 is formed 65 a carton receiver, into which the slide suc-

cessively delivers each carton C and which supports each carton in turn by two vertical edges.

The receiver proper may be considered as embodied primarily by the opposite angles 70 or corners 91, 92 of the receiver casting 90. These corners 91 and 92 together with the catches 122' frame the carton and freely position it so that it can be readily expanded in opening up. 75

The receiver casting 90 is pivotally mounted at 93 to bracket 94 which is mounted on the slide head 10. It is held in position by a loose bolt 95 which can be released readily in case of a jam in the carton 80 receiver. In such an event the casting 90 may be swung on its pivot 93 and the jammed cartons removed without trouble or delay.

To the rear of the diagonal line between 85 the corners 91 and 92 the receiver is hollowed out as at 96 so that the carton as indicated at C is free to expand rearwardly as well as forwardly. This is important as the nature of the opening blade 100 expands 90 the carton slightly while still in its initial position as in Fig. 8 and it is important and I have discovered that it is important to permit the carton to expand symmetrically in both directions in order to avoid 95 distortion and possible tearing.

The lower side of the carton receiving pocket is closed by a plate 110 which is slotted at 111 for the position of the blade 100. In its upward position the blade 100 100 is guided by a similar plate 110' which projects above the pocket member 90. The blade 100 is carried in a slide 101 mounted in a slideway 102 adjustably held to the slide 101 by bolts 101'. The slide 101 is 105 vertically reciprocated by a link 103 connected to one arm 104 with a bell crank pivoted at 105 and having its opposite end provided with a roller 106 running in the cam groove 107 of the cam 108. 110

This cam is fixed on the main shaft 61. The shaft 61 is driven by a sprocket 62' at one end and at its opposite end has a hand wheel 63 by which the machine may be turned over by hand when so desired. 115

The slide 30 carrying the vertically reciprocating blade 100 is itself reciprocated at right angles to the transfer slide 20 by a lever 31. The lever 31 is slotted as at 32 to receive a block 33 held by a stud 34 to the slide 30 so as to vary the throw of the lever with the motion of the slide. The lever 31 is pivoted at its lower end as at 36 and is rocked by a roller stud 37 running in a cam groove in the cam 38 also fast on 120 the power shaft 61.

It will therefore be seen that in this group of parts last described, the blade 100 can be raised past the plane of the plate 110, projecting through the slot 111 so as to pene- 125 130

trate the flat carton C substantially in the line of that one of its flattened out corners which lies facing forward or in the direction in which it is advanced.

5 When the blade 100 enters the carton C at this point it begins to expand it. The carton being held by its edges as above described is free to expand in both directions of its opening movement so that when the blade 100 has passed through it, it is symmetrically opened up with the blade against the inside of what is to become one of its corners, but which up to this time has been pressed flat.

10 The slide 30 now moves forward advancing as the blade 100 which moves the carton out of the opposite corner 91, 92, between which it has been held. (See Figs. 8 and 8^a). As appears in the latter figure it will be noted that the carton C has been 15 brought in contact with a pair of guides 120, 121. These guides converge at first but later become parallel so that the inner corner of the carton meets a slight resistance or drag which tends to swing the adjacent panel about the edge of the knife as a pivot to a position at right angles to that which it occupied when flat. As the blade moves forward this panel traveling against the parallel face of the guide 120 meets 20 no resistance while the forward edge of the opposite panel being still in engagement with the guide face 121 is retarded. In this position as shown in Fig. 8^a the carton is 25 opened out past its normal rectangular position so that the folds or corner-scorings which have been flat prior to opening are given a fold or set in excess of that which is desired. The corners, which have been 30 sharply folded when the carton was flat, are opened out at a more obtuse angle than their ultimate position so as to counteract the tendency of the carton to return to the flat condition in which it was originally.

35 At the end of the movement of the slide 30 along its slideway 39, the blade 100 reaches the inner corner of the carton pocket 140. For the purposes of the present disclosure this pocket need only be considered as one of a plurality of successively presented pockets each adapted to take an 40 opened carton in turn. They are in fact, in the embodiment shown, the receiving pockets of an end flap closing mechanism with which 45 this embodiment is especially adapted to operate.

50 Each pocket 140 has one of its lateral walls 141 pivoted at 142 which is opened by a roller 143 which is moved vertically as indicated by the arrow in Fig. 10 to a position 55 in which it contacts with a tail 144 on the pocket wall. This wall is opened as the blade 100 approaches with the carton trailing thereon.

60 When the blade reaches the corner as 65 shown in Fig. 8^a, the trailing panel clears

the end of the guide 121 and under its own natural tendency this side snaps forward into the pocket. The seating of the carton C in the pocket is assured by the spring pressed return of the wall 141 which snaps 70 against the edge panel and about its corner. The wall 141 has an overhang lip 1¹ which closes about the outer edge, thus holding the carton in position and at the same time giving it a slight diagonal pressure in the 75 direction of the blade, thus completely assuring the completeness of the angular coincidence between the carton and the corners of the pocket.

80 At this point the blade 100 retreats, being lowered along this slideway 102 under the action of a cam 107 through its bell crank and link connection. As soon as the blade has cleared the plate 110, the slide 30 is returned by its cam 38 to its original carton 85 penetrating position beneath the pocket 90. In the meantime the transfer slide 20 has advanced another carton to be opened and positioned it with its edges in the corners 90 and 92.

90 The details of the pocket 90 and the carton engaging edge of the slide 20 are shown in the enlarged fragmentary view of Fig. 7. In this view it will be seen that the edge receiving portions 91, 92, referred to generally as the corners are defined by one wall of the guide 120 and a pair of catches 122' which are just behind the carton when it is delivered into the pocket 90 by the action of the springs 122 which permits that 100 the pawls yield upon the advance of the carton which pushes them out of its path as it is moved forward with the slide. The edge of the slide 20 is provided with a 105 lip 20¹ carefully formed to the exact thickness of the folded carton edge so that it will pick the carton from the end of the pack in the carrier and advance it along the slideway to the carton receiving knife.

110 In order to have the transfer slide 20 accurately and evenly engage the edge of the most advanced carton in the pack and remove it therefore without danger of crumpling or tearing it, it is necessary that the blanks be presented with a uniform 115 pressure as maintained by the ratchet connection 50 and the spring 55 which keeps the conveyor block or follower 45 up against the carton pack. The tension on the spring 55 is restored at frequent intervals by the 120 eccentric 60 which constitutes a continuously acting urge although, through the pawl and ratchet connection, the conveyor is only driven intermittently.

125 It is also important that the cartons be presented in the proper position and that the pack adjacent the transfer slide be squared up and even. This is partly accomplished by the disposition of the rails 43. As above described, there are two of the 130

rails on one side and the third on the opposite side thus affording a three point line of contacts. The action of the jogger 82 restores the alignments of any cartons 5 that may possibly be irregularly positioned in the pack. At each stroke of the cross slide the tail of the lever strikes the side of the carton pack just after the carton has been removed from it, thus assuring not 10 only the alignment of the cartons but their freedom to move up promptly behind the conveyor slide under the pressure of the conveyor driving spring 55.

Extending across the head of the machine 15 and journaled in brackets 11 is a shaft 150 on one end of which is fast at 150¹ a bent rocker arm 151 having its lower end pivotally connected through an intermediate lever 152 to the upper part of the casting of slide 20 30.

Adjacent lever 151 and also fast to shaft 150 is a short arm 153 on the end of which at 154¹ is pivoted a rocker rod 154. This rod is pivoted at its lower end to a rocker 23 155. The rocker 155 is pivotally mounted at 155¹ and carries a block 156 to which is pivoted at 157¹ a slide 157 to operate in the slideway 158 of the guide 48¹.

Suitably mounted within the slide 157 and shouldered to receive a compression spring 159 is a carton urger 157² operated by the upward thrust of the lever 154 to oscillate the rocker 155 around pivot 155¹, all disposed to advance the slide 157, by which 35 means the cartons ahead of the carton urger are also advanced by contact of carton urger to facilitate their delivery to the slide 30 as shown in Figs. 10 and 11.

When the conveyor 41 is advanced by operation of the ratchet drive 50 to advance pack towards slide 20, the cartons contacting with the back side of the carton urger 157² slide along the angular surface 157^a of the carton urger compressing the spring 159, as shown in Fig. 7, and travel the predetermined distance, after which the carton urger returns to an operative position by the expansion of the spring 159.

While I have referred to the machine herein shown in some detail as to mechanisms, it will be understood that many of the mechanisms may be varied and modified or other equivalent mechanisms substituted. All such modifications are to be understood 55 as within the scope of my present invention, and while I have referred to my machine particularly for the handling of cartons, many of its novel features may be utilized in feeding other flat blanks or pieces of stock for subsequent operations.

What I therefore claim and desire to secure by Letters Patent is:

1. In a carton opener, a laterally sloped guide, means for supporting a flat, four-

cornered carton by two opposite folded edges with a flattened fold adjacent said guide, a pointed blade having flat sides disposed transversely of the folded carton and movable longitudinally therethrough in the line of said flattened fold. 65

2. In a carton opener, a laterally sloped guide, means for supporting a flat, four-cornered carton by two opposite folded edges with a flattened fold adjacent said guide, a pointed blade having flat sides disposed transversely of the folded carton and movable longitudinally therethrough in the line of said flattened fold, a rectangular carton 70 receiving pocket having one corner opposite said blade and means for moving said blade past said guide and into said pocket corner to lodge the opened carton therein. 75

3. In a carton opener, a laterally sloped guide, means for supporting a flat, four-cornered carton by two opposite folded edges with a flattened fold adjacent said guide, a pointed blade having flat sides disposed transversely of the folded carton and movable longitudinally therethrough in the line of said flattened fold, a rectangular carton 80 receiving pocket having one corner opposite said blade and including a movable side wall having an engaging edge for the corner diagonally opposite said first-named corner and means for opening said side wall, 85 means for moving said blade past said guide and into said pocket corner to lodge the opened carton therein and means for moving said side wall. 90

4. In a carton opener, means for supporting a flat, four-cornered carton on two folded edges so that it is free to expand in both directions, a pointed blade having flat sides disposed transversely of the folded carton and movable longitudinally therethrough 105 in the line of a flattened fold. 100

5. In a carton opener, means for supporting a flat, four-cornered carton so that it is free to expand in both directions, a pointed blade having flat sides disposed transversely 110 of the folded carton and movable longitudinally therethrough in the line of a flattened fold, a rectangular carton receiving pocket having one corner opposite said blade and including a movable side wall having an engaging edge for the corner diagonally opposite said first-named corner and means for opening said side wall, 115 means for moving said blade into said pocket corner to lodge the opened carton therein and means for releasing said side wall. 120

6. In a carton opener, a pair of guides converging to a parallel spacing less than the width of an opened carton, means for supporting a flat, four-cornered carton by two opposite folded edges with a flattened fold aligned with the parallel wall of one of said guides, a pointed blade having a flat 125

side disposed transversely of the folded carton and movable longitudinally therethrough in the line of said flattened fold.

7. In a carton opener, a pair of guides converging to a parallel spacing less than the width of an opened carton, means for supporting a flat, four-cornered carton by two opposite folded edges with a flattened fold aligned with the parallel wall of one of said guides, a pointed blade having a flat side disposed transversely of the folded carton and movable longitudinally therethrough in the line of said flattened fold, a rectangular carton receiving pocket having one corner opposite said blade and means for moving said blade past said guide and into said pocket corner to lodge the opened carton.

8. In a carton opener, a laterally sloped guide, having an outlet opening of less width than the width of an opened carton, means for supporting a flat, four-cornered carton by two opposite folded edges with a flattened fold adjacent said guide, an opener disposed transversely of the folded carton and movable longitudinally therethrough in the line of said flattened fold.

9. In a carton opener, a laterally sloped guide, means for supporting a flat, four-cornered carton by two opposite folded edges with a flattened fold adjacent said guide, an opener disposed transversely of the folded carton and movable longitudinally therethrough in the line of said flattened fold, a rectangular carton receiving pocket having one corner opposite said blade and including a movable side wall having an engaging edge for the corner diagonally opposite said first-named corner and means for opening said side wall, means for moving said blade past said guide and into said pocket corner to lodge the opened carton therein and means for operating said side wall.

10. In a carton opener, means for supporting a flat, four-cornered carton so that it is free to expand in both directions, an opener movable longitudinally therethrough in the line of a flattened fold, a rectangular carton receiving pocket having one corner opposite said blade and including a movable side wall having an engaging edge for the corner diagonally opposite said first-named corner and means for opening said side wall, means for moving said blade into said pocket corner to lodge the opened carton therein and means for releasing said side wall.

11. In a carton handling machine a conveyor for advancing a stack of vertically disposed knocked down cartons, a cross feed for successively transferring said cartons laterally in their vertically disposed condition, a carton receiver disposed to receive each carton from the cross feed and support

it by its edges, a lateral guide extending from said receiver transversely of said cross feed, a carton opening blade, means for imparting rectilinear motion to said blade to cause it to enter said guideway, and means for imparting rectilinear motion to said blade in a direction at right angles to the entering movement of said blade to cause said blade to carry the carton through said guideway and a receiving pocket for an opened carton and disposed to receive the carton and blade at the forward reciproca- 70 tion of the carrier.

12. In a carton handling machine a conveyor for advancing a stack of vertically disposed knocked down cartons, a cross feed for successively transferring said cartons laterally in their vertically disposed condition, a carton receiver disposed to receive each carton from the cross feed and support 80 it by its edges, inclined lateral guideways extending from said receiver transversely of said cross feed, a carton opening blade, means for imparting rectilinear motion to said blade to cause it to enter said guideway, and means for imparting rectilinear motion to said blade in a direction at right angles to the entering movement of said blade to cause said blade to carry the carton through 85 said guideway and a receiving pocket for an opened carton and disposed to receive the carton and blade at the forward reciproca- 90 tion of the carrier.

13. In a carton handling machine a conveyor for advancing a stack of vertically disposed knocked down cartons, a cross feed for successively transferring each carton laterally in their vertically disposed condition, a carton receiver disposed to receive the cartons from the cross feed and support it by 100 its edges, a carton opening blade, means for imparting rectilinear motion to said blade to cause it to enter said guideway, and means for imparting rectilinear motion to said blade in a direction at right angles to 105 the entering movement of said blade to cause said blade to carry the carton through said guideway and a receiving pocket for an opened carton and disposed to receive the carton and blade at the forward reciproca- 110 tion of the carrier.

14. In a carton handling machine, a feed for said cartons, a carton receiver disposed to receive a carton from the feed and support it by its edges, guideways extending from said receiver, a carton opening blade, means for imparting rectilinear motion to said blade to cause it to enter said guideway, and means for imparting rectilinear motion to said blade in a direction at right 120 angles to the entering movement of said blade to cause said blade to carry the carton through said guideway.

15. In a carton handling machine, a feed for said cartons, a carton receiver disposed 125

to receive a carton from the feed and support it by its edges, guideways extending from said receiver, a carton opening blade, means for imparting rectilinear motion to 5 said blade to cause it to enter said guideway, and means for imparting rectilinear motion to said blade in a direction at right angles to the entering movement of said blade to cause said blade to carry the carton through said guideway, and a receiving pocket for an opened carton and disposed to receive the carton and blade at the forward reciprocation of the carrier.

16. In a carton opener, means for supporting a flat, four-cornered carton by two opposite folded edges with a flattened fold adjacent said guide, a tapered blade having flat sides disposed transversely of the folded carton and having one edge disposed in a vertical line and movable longitudinally therethrough in the line of said flattened fold, a rectangular carton receiving pocket having one corner opposite said vertical blade edge, and means for moving said blade past said 20 guide and into said pocket corner to lodge the opened carton therein.

17. In a carton opener, means for supporting a flat, four-cornered carton by two opposite folded edges with a flattened fold 25 adjacent said guide, a tapered blade having flat sides disposed transversely of the folded carton and having one edge disposed in a vertical line and movable longitudinally therethrough in the line of said flattened fold, a rectangular carton receiving pocket having one corner opposite said vertical blade edge and including a movable side wall having an engaging edge for the corner diagonally opposite said first named 30 corner, means for opening said side wall, means for moving said blade past said guide and into said pocket corner to lodge the opened carton therein and means for moving said side wall.

40. 18. In a machine of the class described, a recessed carton holder having a pair of opposed vertical edge receiving portions positioned freely in advance of said recess, a lateral feed for transferring folded cartons 45 edgewise thereto, an opener vertically reciprocable therethrough, a head having a carton pocket, a slide carrying said opener and reciprocably mounted for motion between said holder and pocket, means for reciprocating the opener and slide to carry said 50 opener and with it the carton through said holder and into said carton pocket.

60. 19. In a machine of the class described, a recessed carton holder having a pair of opposed vertical edge receiving portions positioned freely in advance of said recess, a lateral feed for transferring folded cartons edgewise thereto, an opener vertically reciprocable therethrough, a head having a 65 series of carton pockets, a slide carrying

said opener and reciprocably mounted for motion between said holder and pocket, means for reciprocating the opener and slide to carry said opener and with it the carton through said holder and into said carton pocket, and means for moving said pockets successively into receiving position.

20. In a machine of the class described, a carton holder having a pair of opposed edge receiving portions positioned freely on both sides in a vertical plane, a lateral feed for transferring folded cartons edgewise thereto, an opener vertically reciprocable therethrough and expanding transversely thereof, a rectangular carton pocket, a slide carrying said opener and reciprocably mounted for motion between said holder and pocket in line with one corner thereof, and means for reciprocating the opener and slide to carry said opener and with it the carton through said holder and into said carton pockets.

21. In a machine of the class described, a carton holder having a pair of opposed edge receiving portions positioned freely on both sides in a vertical plane, a lateral feed for transferring folded cartons edgewise thereto, an opener vertically reciprocable therethrough and expanding transversely thereof, a head having a series of rectangular carton pockets, a slide carrying said opener and reciprocably mounted for motion between said holder and pockets in line with one corner thereof, means for reciprocating the opener and slide to carry said opener and with it the carton through said holder and into said carton pockets, and means for moving said pockets successively into receiving position.

22. In a machine of the class described, a carton holder having a pair of opposed edge receiving grooves positioned freely in a vertical plane, a lateral feed for transferring folded cartons edgewise thereto, an opener vertically reciprocable therethrough, means for reciprocating said opener vertically to cause said opener to enter said holder, and means for subsequently reciprocating the opener at right angles to said vertical movement to cause said opener to carry the carton through said holder.

23. In a carton feeding and opening machine, a conveyor for supporting and feeding a plurality of collapsed cartons, a carton pocket, an opener blade operating between said conveyor and said pocket, and means for successively imparting to said blade rectilinear motion in two successive angular directions to cause it to first enter and partially open a carton and to subsequently transfer said carton to said pocket.

24. In a carton feeding and opening machine, a conveyor for supporting and feeding a plurality of collapsed cartons, a car-

ton pocket, an opener blade operating between said conveyor and said pocket, and means for successively imparting to said blade rectilinear motion in two successive angular directions to cause it to first enter and partially open a carton and to subsequently transfer said carton to said pocket, and a carton receiver in advance of said carton pocket constructed and arranged to co-act with said blade to fully open the carton prior to its insertion into said pocket.

25. In a carton feeding and opening machine, a conveyor for supporting and feeding a plurality of collapsed cartons, a carton pocket, a carton transfer mechanism operating between the delivery end of said conveyor and said pocket, and including a carton opening device, and means for successively imparting to said carton opening device rectilinear motion in two successive angular directions to cause it to first enter and partially open a carton and to subsequently transfer said carton to said pocket.

26. In a carton feeding and opening machine, a horizontally disposed conveyor for supporting and feeding a plurality of collapsed cartons in vertically edgewise juxtaposed position, a carton pocket, a carton transfer mechanism operating between said conveyor and said pocket, and including a carton opening blade, and means for successively imparting to said blade rectilinear motion in two successive directions at substantially right angles to each other to cause

it to first enter and partially open a carton 35 and to subsequently transfer said carton to said pocket.

27. In a carton feeding and opening machine, a conveyor for supporting and feeding a plurality of collapsed cartons, a carton pocket, a carton transfer operating between said conveyor and pocket and including a carton opening device, and means for successively imparting to said device rectilinear motion in two successive angular directions to cause it to first enter and partially open a carton and to subsequently transfer said carton to said pocket. 40 45

28. In a carton feeding and opening machine, a conveyor for supporting and feeding a plurality of collapsed cartons, a carton pocket, a pair of spaced guides disposed between said conveyor and pocket, a carton opening blade operating between said guides, and means for successively imparting to 50 said blade rectilinear motion in two successive angular directions to cause it to first enter and partially open a carton and to subsequently carry said carton past said guides into said pocket. 60

29. In a carton pocket, a blade, and means for successively imparting to said blade rectilinear motion in two angular directions to cause it to first enter and partially open a carton and to subsequently carry the carton 65 into said carton pocket.

In testimony whereof I affix my signature.
GEORGE A. ROBINSON.
